UNITED STATES PATENT OFFICE.

FRANKLIN LAWRENCE, OF PORTLAND, MAINE, ASSIGNOR TO PORTLAND STOVE FOUNDRY CO., OF PORTLAND, MAINE, A CORPORATION OF MAINE.

DRAFT REGULATOR FOR FIREPLACES AND THE LIKE.

Application filed April 27, 1928. Serial No. 105,020.

This invention relates to improvements in draft regulators for fire places and the like. It relates more particularly to improved means for operating such regulators, and to 5 a structure for the apparatus as a whole which lends itself to the packing, storing and shipping of a quantity of the regulators with considerable saving in time, labor and space. The commonly used type of fire place draft 10 regulator embodies a damper mounted in a casing, which latter serves as the bridge over the fire place opening in the room as well as comprising the entrance to the flue. In modern homebuilding the location of the 15 means for operating the damper has become important, and is the occasion of careful consideration by architects and contractors as well as of particular home builders, and incidentally a source of trouble and expense for 20 dealers which it is among the objects of this invention to eliminate. Building methods have standardized to a degree the positions at which the operating means may be placed, in either of two usual arrangements, 25 one being above the fire place opening, projecting into the room, and the other within the fire place opening practically concealed from view. Each arrangement has its own advantages and appeal, and as a result it has 30 been necessary heretofore that at least two distinct types of regulating apparatus be manufactured, each with its own separate and distinctive style of damper and casing therefor; and the dealers in such apparatus 35 have had to carry both types in stock. The customary structures are moreover cumbersome, and thus a large space for storage of each type is needed if any considerable number is carried in stock. In shipment and com- 40 mercial distribution the bulky nature is also a source of trouble and expense.

It is a purpose of the present invention to eliminate the necessity for carrying in stock more than a single type of regulator, by providing apparatus capable of serving in either 45 of the dual capacities, with the operating lever projecting to the face of the fire place either through the wall above the fire place opening, or at a lower lever terminating 50 within said opening and not projecting into the room, according as one or the other arrangement is desired. It is a feature of the improved structure that a choice between these arrangements may be made when the 55 apparatus is installed, the same elements

serving for either. A further object is to provide a structure whereby the regulators may be nested together for shipment and storage so that a considerable space is conserved, and shipping and storage costs are 60 reduced.

These ends are gained by setting the damper at the top of the tapering walls forming the regular casing, with its axle pins resting in notches in the tops of the end walls of the casing. The operating device for the pivoted damper is a push rod depending within the casing, thrust up or down by an arm on a rock shaft, which shaft has the operator's handle, runs from the front to back, 65 is itself capable of being set in either of two elevations in the casing, and in various positions as regards depth from front to back. In this arrangement the said arm is slidable on a squared portion of the rock shaft, and 70 is arranged to take hold of the push rod in either of two places at different elevations thereon, according as the rock shaft is in its upper and forward position, projecting through the wall into the room or is in its 75 lower and rearward position, not projecting into the room but set in the fireplace opening. When shipping or storing the regulators, the rod and shaft may be removed and packed in a thin box and thus placed in the casing, and a number of casings with their 80 operating parts may then be nested together in compact piles, the successive units being spaced apart by internal ribs on their sloping walls.

It is intended that the patent shall cover, by suitable expression in the appended claims, whatever features of patentable novelty exist in the invention disclosed.

In the accompanying drawings:

Figure 1 is a front elevation of apparatus constructed according to the invention, the flanged casing thereof being arranged above a fire place in position to be built into its walls as bricks are subsequently laid above the casing flanges, the operating rod being in position to extend out through the wall, above the fire place but with part broken away to a section on line 1-1 of Figure 2;

Figure 2 is an elevation, in section on line 2-2 of Figure 1 except that the connections to the damper are left intact, the damper operating means being in their through-the-wall arrangement;

Figure 3 is a view like Figure 2 showing 110

the in-the-fireplace-opening arrangement of the damper operating means;

Figure 4 is a bottom plan;

Figure 5 is an elevation in section on line 5-5 of Figure 4;

Figure 6 is a detail view showing the means for locking the rock shaft in place; and

Figure 7 is a side elevation of a group of regulators nested together for storage or shipment.

Referring to the drawings, there is seen a fire place 10 having the usual flue 12 above it. The damper and regulator casing 14 is installed in the usual manner at the entrance to 15 the flue, with its horizontal front flange 15 serving as the bridge for supporting the facing bricks 16 above the fire place. The passage through casing 14 becomes gradually smaller toward the top of the casing, and the 20 damper 18 is mounted for turning at the top of said casing. The advantages gained by so shaping the casing are the nesting, which is very useful in connection with the shipping and storing of the regulators. In Figure 2 an operating rod is shown which in the present instance is a rock shaft 20 extending into the room through the facing bricks which may be understood to rest on the front flange 15, between the side columns 16'. 30 This rock shaft passes horizontally through the casing 14 and has bearings in holes 22 in the front and rear casing walls. As illustrated at 14^a (Figures 2, 3, 4) the wall at the rear right hand corner has a re-entrant portion, which supports the shaft, and the top part of the adjacent end wall is also slightly depressed as at 14^b. This construction by permitting of the use of a shorter shaft than would otherwise be required when in the forward position of Figure 2, provides so that its rear end does not project unduly beyond the rear of the casing when arranged in its position of Figure 3.

In the arrangement of Figure 2 the forward 45 end of the shaft passes through the front wall of the casing and through an anchor element 23 adapted to be maintained rigid by the facing brick. The forward extremity of the anchor constitutes a flange for engaging 50 the front wall of the fireplace, and the central hole therein through which shaft 20 extends has an enlarging notch 23^a at one point, (Figure 6) through which a lug or projection 20^a on shaft 20 is adapted to pass so as to 55 lock the shaft in place when it has been turned therein. The said slot and projection are so arranged that when the yoke 24 and thrust rod 26 are connected to the damper the projection cannot register with the slot, 60 and thus the shaft 20 may not be pulled out. A handle comprising a cross arm 28 may be provided on the forward end of shaft 20 to facilitate its being turned.

In the arrangement of the operating mech- 65 anism shown in Figure 2 the yoke 24 must be

held against sliding on the squared portion of shaft 20. For this purpose a pair of ribs 14^c are provided on the end wall of the casting, embracing the yoke 24 in a manner to form a pocket within which the yoke may 70 rock with shaft 20 but by which it is prevented from sliding along the shaft. The ready adjustability of the operative parts provides for varying thicknesses of the facing brick, in that the shaft 20 may assume various positions 75 with respect to the yoke and will be operative alike in all of said positions.

Figure 3 shows the rock shaft 20 combined with the very same operative elements so as to have its operating handle 28 within the fire place opening. The yoke 24 in this arrangement is slid forward so as to abut against the shoulder 20^b on the shaft; is connected to the thrust rod 26 at a different position, to wit, at the end thereof; and the 80 rock shaft 20 is slid further through the rear casing wall and penetrates it through a different hole 32, while its forward end is in a bearing 30 provided beneath the front horizontal flange of casing 14. The shaft 20 is 85 locked in position in like manner as in the other arrangement, there being a flange and slot on the bearing 30 serving like those on anchor 23, and the projection 20^a on shaft 20 cooperates with them to maintain the 90 shaft in place. The yoke 24, in this arrangement, requires no means for holding it against sliding, as the incline of the shaft keeps it 95 always against the shoulder provided where the squared portion of the shaft ends. In 100 both described arrangements of the operating means there is a positive control for the damper, and in each case the actual position of the damper will be indicated at all time by the direction assumed by cross arm 105 28 of the handle. Although two holes in the rear wall of the casing 14 are shown, one for receiving the rear end of rock shaft 20 in each of its alternative positions, a single hole may be so arranged and so shaped 110 that it will accommodate the shaft 20 in both of its operative positions.

Conservation of space in shipping and storing is an important result made possible by the illustrated structure of the casing 14, 115 by which each fits snugly within another. In furtherance of this end, the interior faces of the front and back casing walls are provided with the ribs 14^c. These, which need be only of slight proportions, and of which four will suffice, are suitably arranged so as to engage the outer faces of the sloping walls of the casing next below it in a pile to hold the tops of adjacent casings in spaced 120 relation. The shafts, yokes, and rods may be removed and stowed differently in their respective casings; or they may be grouped and secured to the flange of the casings externally thereof. Figure 7 of the drawings 125 the lower casings of the pile each has a thin 130

box 34 arranged on the flange of the casing, containing the operating parts, while in the upper one of the pile the box of parts is shown by dotted lines arranged within the 5 casing in the space provided between the tops of the nested casings. The latter arrangement is the preferred one as the possibility of accidental detachment and loss of parts is eliminated.

10 Thus are provided all of the advantages of prior dampers, but at a considerable saving in space, in time and cost of manufacture, and of shipment and storage, with much greater economy and utility from the stand- 15 point of the dealers in such articles.

I claim as my invention:

1. A draft regulator for fire places comprising in combination a casing having a rear bearing, and two forward bearings arranged one above the other; a damper pivotally mounted in said casing; and operating means connected to the damper and capable of two different arrangements; said operating means being adapted to be supported by 20 said rear bearing and the upper of said forward bearings to effect positioning of its front end forward of the plane of the face of the fire place above the latter's opening, and being adapted to be supported by 25 said rear bearing and the lower of said forward bearings to effect positioning of said end behind said plane within said opening.

2. In a draft regulator for fire places the combination with the damper thereof of operating means for the damper adapted to be arranged with its forward portion mounted at one elevation whereby it extends beyond the plane of the face of the fireplace above the latter's opening for access by the operator, and adapted to be arranged with its forward portion mounted at another elevation whereby it terminates short of said plane and within said opening for access thereby the operator.

45 3. A draft regulator for fire places comprising a casing with a damper pivoted therein; a thrust rod depending from the damper within the casing; an operating rod extending from front to rear of the casing and adapted to engage the thrust rod; and mounting means for said operating rod provided on the casing at two different elevations, by 50 one of which the operating rod may stand with the range of operating travel of its front end at an elevation above the bottom of said casing, and by the other of which the same may stand below the bottom of said casing.

60 4. A draft regulator for fire places comprising in combination a casing; a damper pivoted on the top edge of the casing; a connecting element depending therefrom within said casing; an operating rod extending from front to back of the casing and capable of 65 two different arrangements; means adjusta-

ble longitudinally of said rod for effecting engagement between it and the said connecting element; and means for supporting said rod in each of its said arrangements, comprising a rear bearing and upper and lower 70 front bearings; the said rod, when supported by the rear bearing and the upper front bearing, extending beyond the plane of the face of the fire place above the latter's opening, and, when supported by the rear 75 bearing and the lower front bearing, terminating short of said plane and within said opening.

5. A draft regulator for fire places comprising a casing whose front, back and both end walls are inclined inward from bottom to top, two of said walls being provided with internal protuberances; a damper pivoted at the top of the casing; and removable operating elements, for engaging the damper, 80 reaching from the face of the fire place into the casing; the said casing being adapted to nest with others like it, and the said protuberances being positioned to engage the outside of the sloping walls of a similar casing 85 next below it in a stack thereby to provide a space between adjacent casings in the stack; and the said removable elements of the regulator being adapted to be packed together 90 within limits less than the said space. 95

6. A draft regulator for fire places comprising in combination a casing whose rear wall has a re-entrant portion; a damper pivoted at the top of the casing; and removable operating elements for engaging the damper including an operating rod which extends 100 inward from the plane of the face of the fireplace and is slidably mounted with a bearing in said re-entrant portion, whereby the extent of the projection of said rod forward from said re-entrant portion may be varied. 105

7. A draft regulator for fire places comprising a casing including a wall extending from front to rear; a pair of internal projections side by side on said wall; a damper pivoted in the casing; an operating rod extending from front to rear of the casing and having a squared portion; means at the front at two elevations, one of them being below the casing and each being for supporting 110 said operating rod; a slideable element mounted on the squared portion of the rod, adapted to be turned thereby, and having a connection to the damper; the said element being engaged between the said internal projections and thereby maintained in operative position on the shaft, when the latter is in its upper elevation; and the said rod, when in its lower elevation, being tipped downward and having a shoulder against which the said element may rest. 115 120

8. A draft regulator for fire places comprising in combination a casing whose rear wall has a re-entrant portion; a damper pivoted at the top of the casing; an operating 125 130

rod extending to the face of the fire place and having a squared portion; an arm adjustable longitudinally along said squared portion of the rod; and a connecting element depending from the damper and adapted to be engaged by said adjustable arm; the said rod being slidably and rotatably mount-

ed with a bearing in said re-entrant portion of the casing, whereby the extent of projection of the rod forward from said re-entrant portion may be varied. 10
